BEEHIVE PRESS

Carl List, Elmont, N. Y.

Application February 3, 1933. Serial No. 654,980

4 Claims. (Cl. 6—12)

This invention relates to new and useful improvements in a beehive press.

The invention has for an object the construction of a beehive press which is characterized by 5 a provision whereby the honeycomb is treated in a certain fashion so that it releases absolutely the greatest amount of wax.

As a still further object of this invention, it is proposed to include within the process a plurality of chains adapted to imbed themselves into the honeycomb during compression so that upon subsequent release the chains serve to cut the honeycomb and so disturb it for the efficient discharge of the wax.

15 It is a still further object of this invention to provide an arrangement whereby the chains may be radially adjusted to compensate for different conditions of the honeycomb particularly its mass as related to the size of the press.

20 As a still further object of this invention, it is proposed to so construct the bee-hive press that necessary steam and motion are obtained for the most efficient discharge of the wax.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a transverse sectional view of a device constructed according to this invention.

Fig. 2 is a sectional view taken on the line 2—2 of Fig. 1.

40 Fig. 3 is a fragmentary enlarged detailed view of a portion of Fig. 1 showing in particular the lower right hand end corner of a cylindrical casing of the device.

Fig. 4 is a fragmentary enlarged detailed view 45 of another portion of Fig. 1 showing in detail the attachment of the chains.

Fig. 5 is a sectional view taken on the line 5—5 of Fig. 4.

Fig. 6 is a side elevational view of the device.

50 The beehive press according to this invention comprises a cylindrical casing 10 with a bottom discharge spout 11. A threaded spindle 12 is relatively mounted coaxially through the casing 10. A perforated drum 13 is rotatively mounted on 55 the spindle 12 and located within the casing 10.

The casing 10 is composed of a sheet metal cover engaged upon an end cap 14 at one end and upon a ring 15 at the other end. This ring is provided with a flange to which a removable end cap 16 is secured by wing nuts 17.

60 A means is provided for rotating the spindle 12 and comprises a hand wheel 18 secured upon the extended square end 19 of the spindle. The wing nut 20 holds the hand wheel 18 in place. Another means is provided for rotating the drum 13 and comprises an end disc 21 secured upon one end of the drum 13 and having a sleeve portion 22 arranged on the spindle 12 and extending to the exterior. A handle 23 is mounted upon the sleeve 22 whereby the sleeve may be turned 70 for turning the drum. The handle 23 is connected with the sleeve by the provision of a set screw 24 which arrangement permits loosening of the set screw so that the handle may be removed. Another set screw 25 is mounted upon 75 a tubular portion of the end cover 16 and is adapted to engage against the sleeve 22 for locking the drum 13 against turning. A small set screw 26 is engaged through the sleeve 22 and is adapted to connect with the spindle 12 to connect the 80 drum 13 and the spindle 12 in unitary rotation. The drum 13 comprises a perforated sheet attached at one end upon an end plate 27 rotative on the spindle 12 and at the other end upon the ring 28 detachably connected with the end cap 85 21. A disc 29 is mounted upon the spindle 12 and on the inside of the end cap 21.

80 A perforated plate 30 is disposed within the drum 13 and is of a diameter to slide within the drum. This perforated plate 30 is threadedly engaged upon the spindle 12. A plurality of guides 31 are mounted upon the inside of the drum 13 and engage through slots in the perforated plate 30 so as to limit motion of the plate along the longitudinal axis only. The end disc 27 is also 90 provided with a tubular portion provided with a set screw 32 adapted to engage against the spindle 12 for locking the spindle against rotation when desired.

95 A steam supply is associated with the device 100 and comprises a receptacle 33 adapted to hold water and furthermore adapted to be placed upon a flame for the generation of steam. A pipe 34 connects with the top of the receptacle 33 and terminates in branches 35 and 36. The 105 branch 35 discharges coaxially into the spindle 12 which is hollowed out along its complete length for this purpose. The steam in the spindle can discharge from a plurality of radial openings 37 in the spindle. The branch pipe 36 discharges 110

into the casing 10. Each of the pipes 35 and 36 is provided with a valve 38 for the control of the steam.

A provision is made for collecting the wax discharge. This arrangement comprises a funnel 39 mounted within the bottom discharge 11 and extending immediately over a strainer 40 supported upon a ring 41 arranged within a tubular member 42 placed upon the top of the receptacle 33.

10 Another funnel 43 is mounted within the top of the receptacle 33 and has a discharge 44 to the exterior. The tubular member 42 is provided with handles 45 to facilitate its removal from the top of the container 33.

15 A means is provided for breaking the honeycomb during the operation of compression and releasing it for the purpose of efficiently causing the discharge of the wax. This means comprises a plurality of chains 46 stretched between the perforated plate 30 and a yoke 47 mounted upon the spindle 12. The yoke 47 has one of its arms formed with a slot 48 engaging one of the guides 31 so as to prevent its free rotation and to cause it to rotate along with rotation of the drum 13 and consequently the perforated disc 30. An arrangement is provided whereby the radial positions of the chains 46 may be varied to adjust the device for different conditions in use. More particularly each of the ends of the chains 46 is connected with slides 49 mounted within guides 50 secured respectively upon the inner sides of the perforated disc 30 and the yoke 47. Each of the slides 49 is provided with a set screw 51 acting against the guides 50 whereby the slides may be clamped in various radial adjusted positions.

20 The casing 10 is provided with a thermometer 52 so that the internal temperature of the casing is known. The receptacle 33 is provided with several nipples 53 closed with caps 54 so that water may be placed into the receptacle or removed. The tubular member 42 is provided with a bulged portion 55 whereby it may be conveniently raised by the top of the receptacle 33.

25 At the top the tubular portion 42 is provided with a rolled edge 56 forming a rest for a bulged portion 57 arranged upon the discharge 11.

30 The operation of the device is as follows: First the honey is extracted and then the honeycomb cleaned. Then the hand wheel 18, the handle 23, the end caps 16 and 21 and the end plate 29, are removed and the honeycomb placed within the open end of the drum 13. Then the removed parts are replaced. Next water is placed

35 into the receptacle 33 and the device supplied with sufficient heat to create steam. The steam is allowed to enter the spindle 12 so as to prevent the wax from sticking upon the spindle and prevent operation of the perforated disc 30 as hereinafter explained.

40 Furthermore, the steam may enter the casing 10 to raise the internal temperature sufficiently to cause the melting of the wax. Then the spindle 12 is rotated by turning the hand wheel 18 and the perforated plate 30 is caused to advance along the spindle and compress the honeycomb. During the stages of compression the handle 23 is rotated to rotate the drum 13 and allow the melting wax to run off. During the compression 45 of the honeycomb the chains 46 will imbed themselves into the honeycomb material. The wax which runs off is directed first through the funnel 39 then into the strainer 40 and then by the funnel 43 to the discharge 44 where it may

be suitably collected. Impurities of large size remain in the strainer.

50 The hand-wheel 18 should be turned first in one direction to slightly compress the honeycomb and then turned back so as to cause the chains 46 to straighten out and cut the honeycomb. In this manner the process is proceeded on until the honeycomb has been completely compressed and the wax efficiently removed. During the operation as the size of the honeycomb diminishes due to the loss of wax, and also in cases where the honeycombs are of different sizes, it is advisable to adjust the radial positions of the chains 46. This may be conveniently done by loosening set screws 51 and moving the slides 49 to desired positions within the guides 50. A slight turn upon the set screw 20 causes simultaneous rotation of the spindle 12 and the drum 13 which is desirable during the process so as to eliminate the necessity of individually operating these parts. The guides 31 prevent the perforated disc 30 from turning, limiting its motion to the longitudinal only.

55 While I have shown and described the preferred embodiment of my invention, it is to be understood that I do not limit myself to the precise construction herein disclosed and the right is reserved to all changes and modifications coming within the scope of the invention as defined in the appended claims.

60 Having thus described my invention, what I claim as new and desire to secure by United States Letters Patent is:—

1. A beehive press, comprising a cylindrical casing with a bottom discharge spout, an externally threaded hollow spindle rotative within said casing, a perforated drum rotative on said spindle, means for rotating said drum, means for rotating said spindle, a perforated plate threadedly engaged upon said spindle and of a diameter snugly engaging within said drum, guides mounted within said drum limiting motion of the perforated plate to longitudinal movement only, a steam supply within the said cylindrical casing and also within said hollow spindle means for breaking the honeycomb during the compressed action of said perforated plate in its motion back and forth, comprising a yoke mounted upon said spindle chains extending longitudinally within said drum and mounted on one of their ends upon said perforated disc and at their other ends upon said yoke and connected for unitary rotation with said drum, and means for adjusting the radial positions of said chains.

110 2. A beehive press, comprising a cylindrical casing with a bottom discharge spout, an externally threaded hollow spindle rotative within said casing, a perforated drum rotative on said spindle, means for rotating said drum, means for rotating said spindle, a perforated plate threadedly engaged upon said spindle and of a diameter snugly engaging within said drum, guides mounted within said drum limiting motion of the perforated plate to longitudinal movement only, a steam supply within the said cylindrical casing and also within said hollow spindle means for breaking the honeycomb during the compressed action of said perforated plate in its motion back and forth, comprising a yoke mounted upon said spindle chains extending longitudinally within said drum and mounted on one of their ends upon said perforated disc and at their other ends upon said yoke and connected for unitary rotation with said drum, and means for adjusting the radial positions of said chains.

positions of said chains, comprising slide members connected with said chains, radial guide members associated with said slides, and means for holding said slides in various adjusted positions within said guides.	with said slides, and means for holding said slides in various adjusted positions within said guides comprising set screws engaged through said slides and abutting against the guides for accomplishing the holding of the slides in various adjusted positions.	80
5. A beehive press, comprising a cylindrical casing with a bottom discharge spout, an externally threaded hollow spindle rotative within said casing, a perforated drum rotative on said spindle, means for rotating said drum, means for rotating said spindle, a perforated plate threadedly engaged upon said spindle and of a diameter snugly engaging within said drum, guides mounted within said drum limiting motion of the perforated plate to longitudinal movement only, a steam supply within the said cylindrical casing and also within said hollow means for breaking the honeycomb during the compressed action of said perforated plate in its motion back and forth, comprising the yoke mounted upon said spindle chains extending longitudinally within said drum and mounted on one of their ends upon said perforated disc and at their other ends upon and yoke mounted upon said spindle and connected for unitary rotation with said drum, and means for adjusting the radial positions of said chains, comprising slide members connected with said chains, radial guide members associated	4. A beehive press, comprising a cylindrical casing with a bottom discharge spout, an externally threaded hollow spindle rotative within said casing, a perforated drum rotative on said spindle, means for rotating said drum, means for rotating said spindle, a perforated plate threadedly engaged upon said spindle and of a diameter snugly engaging within said drum, guides mounted within said drum limiting motion of the perforated plate to longitudinal movement only, a steam supply within the said cylindrical casing and also within said hollow means for breaking the honeycomb during the compression action of said perforated plate in its motion back and forth, said collecting receptacle comprising a tubular member engaged upon said spout, a water container engaged within the free end of said tubular member, a funnel within said spout, a strainer within said tubular member beneath said funnel, 100 and a funnel with a discharge pipe beneath said strainer.	85
